UNITED STATES PATENT OFFICE.

FRANCIS KARR, OF HOLLAND, MICHIGAN.

SPRING BED-BOTTOM.

1,205,901.

Specification of Letters Patent. Patented Nov. 21, 1916.

Application filed November 12, 1914. Serial No. 871,790.

To all whom it may concern:

Be it known that I, FRANCIS KARR, a citizen of the United States, residing at Holland, in the county of Ottawa and State of Michigan, have invented certain new and useful Improvements in Spring Bed-Bottoms, of which the following is a specification.

My invention relates to improvements in that class of spiral spring bed bottoms that is made up of several spirals whose surface construction is connected by a series of helical springs in lieu of the ordinary tie rods, and its objects are: First, to provide against the possibility of the upper, or surface coils of the springs turning or slipping in their fastenings. Second, to render the surface construction absolutely flexible and free from uneven ridges. Third, to eliminate the possibility of the connections between the surface coils of the springs sliding or grating upon each other and thus producing squeaking sounds as the occupant moves from one position to another. I attain these objects by the peculiar line of construction shown in the accompanying drawing, in which—

Figure 1 is a plan of the upper coil of a spring showing the relative positions of the several elements of this bed spring, and the manner of connecting the same. Fig. 2 is an enlarged view of a part of a surface coil showing more distinctly the manner of connecting and securing the helical connecting-springs with the surface coils of the several springs. Fig. 3 is an elevation of a short piece of the surface coil of the spiral spring showing its connection with the helical springs as seen if looking from the center of the surface coil of the spiral spring.

Similar letters refer to similar parts throughout the several views.

A represents the surface coil of a spiral spring.

B represents the continuation of the coil, and C, C are the helical connecting-springs. This invention consists of the manner of connecting these helical connecting-springs with the surface coils of the spiral springs by placing the terminal coils of the helical connecting-springs C against the outer surface of the surface coil of the spiral spring A, then carrying the tangentially extended end C' of the helical spring over the said surface coil, and one or more times around the same, as indicated at c c in the several

figures, then through the terminal coil of the next succeeding helical connecting-spring, as indicated in Figs. 1 and 2, and more plainly shown in Fig. 3, so this coil will be firmly clamped between this part of the tangential extension of the preceding helical spring C and the adjacent surface of the spring A, and the end c' of said tangential extension finally securely wound, in a reverse direction, around the terminal coil A and the beginning of the tangential extension C' of the next helical connecting-spring C. It will be readily understood that by this manner of securing the helical connecting-spring C to the surface coil A of the main spiral spring, that is, with the part C' of the helical spring C passing over the surface coil A and the end of the next preceding helical-connecting-spring C passing through the terminal coil of the succeeding helical connecting-spring C, as shown, the helical connecting-springs are so firmly secured to the surface coils A that it will be impossible for them to move or slip upon the surface coils A to cause any grating or squeaking or other unpleasant noises as the occupant of a bed moves to change his position.

C' represents the appearance of the tangential ends of the helical connecting-springs C before they are interwoven with the surface coil A of the spiral spring, as indicated at C' in the several views.

At D I have shown a diagonal helical connecting-spring which is connected with the spring A, as at D'; and on to d, d', practically in the same manner that the tangential ends C' of the helical connecting springs C are connected therewith. When this diagonal helical connecting-spring is used, only one can be used in one space between spiral springs, as otherwise the springs would cross each other and cause disagreeable grating noises.

What I claim as new, and desire to secure by Letters Patent of the United States, is:

1. In combination with the surface coils of a spiral spring bed bottom, helical connecting-springs radiating at right angles from four given points on the surface coils and having tangential extensions, said tangential extensions passed around the surface coils and then to and through the terminal coil of the next succeeding helical connecting-spring, and then securely connected with the surface coil and the beginning of the tangential extension of the said next suc-

ceeding helical connecting-spring, and diagonal helical connecting-springs connected with the surface coils in like manner.

2. In combination with the surface coils of a spiral spring bed bottom, helical connecting-springs radiating at right angles from four given points on the surface coils and having tangential extensions, said tangential extensions passed around the surface coils and then to and through the terminal coils of the next succeeding helical connecting-spring, and then securely connected with the surface coil and the beginning of the tangential extension of the said next succeeding helical connecting-spring.

3. In combination with the surface coils of a spiral spring bed bottom, helical connecting-springs having tangential extensions locked to the said surface coils by the tangential extension of each helical connecting-spring being passed over and around the surface coil to and through the terminal coil of the next succeeding helical connecting-spring, then in the reverse direction wound tightly around the surface coil and the beginning of the tangential extension of the said next succeeding helical connecting-spring, thus locking each helical connecting-spring tightly to the surface coil of the spiral spring by means of the tangential extension of the next preceding helical connecting-spring, as shown and described.

4. In combination with the surface coils of spiral spring bed bottoms, and with the

helical connecting-springs having tangential extensions, the tangential extensions of the said helical connecting-springs placed upon the surface coils, then carried over and around the same to and through the terminal coils of the next succeeding helical connecting-spring and securely connected with the surface coils and the beginning of the tangential extension of the next succeeding helical connecting-spring, each helical connecting-spring secured to the surface coil in like manner.

5. In combination with the surface coil of a spiral spring bed bottom, helical connecting-springs having tangential extensions and radiating from given points on the surface coils, the tangential extensions of each helical connecting-spring passed over and around said surface coil to and through the terminal coil of the next succeeding helical connecting-spring, and then in a reverse direction around the surface coil and the beginning of the tangential extension of the said succeeding helical connecting-spring, thus locking each helical connecting-spring firmly and positively to the surface coil by means of the tangential extension of the next preceding helical connecting-spring.

Signed at Grand Rapids Michigan November 9, 1914.

FRANCIS KARR.

In presence of—

I. J. CILLEY,
JOSEPH RENIHAN.
